UNITED STATES PATENT OFFICE.

CHARLES V. A. ELEY, OF EDGBASTON, BIRMINGHAM, ENGLAND.

COLLISION-MAT FOR USE ON SHIPS.

1,309,022.

Specification of Letters Patent.

Patented July 8, 1919.

Application filed October 31, 1918. Serial No. 260,565.

To all whom it may concern:

Be it known that I, CHARLES VICTOR ALBERT ELEY, a subject of the King of Great Britain, residing at 10 Cambridge Crescent, 5 Edgbaston, Birmingham, in the county of Warwick, England, have invented a new and useful Collision-Mat for Use on Ships; and I do hereby declare the following to be a full, clear, and exact description of the 10 same.

This invention relates to collision mats for use on ships and refers more particularly to that class of such which comprises a sheet of rubber or equivalent material to 15 which are secured a number of parallel bars adapted to bridge a hole in a ship and permitting the mat to be rolled up when not in use.

The main object of the invention is to 20 provide a mat which is more efficient in use and more easily placed in position; and in accordance therewith it comprises a sheet of a rubber or equivalent material and a number of flat spring strips to which are connected a series of planks and there are preferably also provided a number of metal tubes or their equivalents for reinforcement 25 of the planks. The collision mat is provided with suitable means of suspension, and the 30 parts are preferably so arranged that the mat can be rolled up when not in use.

A further feature of the invention relates to means whereby two or more mats may be joined together so as to function as one 35 large mat when required for use with large holes. One edge of the mats is for this purpose provided with projections or spigots and the other edge with sockets or tubes, two mats being joined together by engaging 40 the spigots of one mat with the sockets of another mat.

Referring to the drawings:—

Figure 1, is an outer face view of two collision mats according to this invention, 45 slightly separated but indicating the manner in which the two mats are to be joined together.

Fig. 2, is a side elevation of same in its operative condition.

Fig. 3, is a similar view rolled up as when 50 not in use.

Fig. 4, is an enlarged sectional view showing the manner in which the adjacent ends of two mats are detachably connected together.

Fig. 5, is a side elevation showing the manner in which the mat may be secured to vertical girders employed to bridge a horizontally disposed hole of a length greater than the width of the mat. 60

Fig. 6, is a plan of part of same.

In one construction of mat according to this invention and as shown upon the accompanying drawings the rubber or equivalent sheet 1 has attached on one face vertical or approximately vertical flat springs 2 spaced at suitable distances apart. A series of wooden planks 3 are secured to said springs so that they run at an angle, preferably a right angle, to the same, these 70 planks being spaced suitable distances apart or disposed close together. The collision mat is suspended in position on the hull or other part of the vessel and is normally rolled up, as seen in Fig. 3, and retained in 75 its rolled condition by suitable fastenings (not shown). The position of the collision mat is such that the rubber sheet will face the hull. When the fastenings are released the collision mat will unroll even 80 when immersed in water so as to cover a hole in the hull while the wooden planks serve to bridge the hole.

The steel springs may have imparted to them a natural curvature corresponding approximately with the curvature of the hull or a particular part of the hull and the collision mat therefore falls, when released, to a configuration approximately corresponding with that of the hull, the pressure of 90 the water on the outside of the mat forcing it to a curvature corresponding with that of the hull.

The wooden planks are preferably arranged to run horizontally from end to end 95 of the collision mat as shown.

To the wooden planks there may be longitudinally secured steel tubes 4, rods, or the like for the purpose of reinforcing said planks. 100

Means may be provided on the collision mats for connecting adjacent collision mats together. These means may consist of projections on some or all of the ends of the tubes or the like and sockets on the other 105 ends thereof, such projections and sockets being so arranged that they can be engaged or telescoped to connect two or more collision mats together as shown in Fig. 4. Where tubes are employed, the bores of the 110

same may serve as sockets at one end. Cotter pins as 5 may be employed for securing the projections and sockets in engagement.

A suitable means of suspension consists 5 of staples (not shown) secured upon the hull and hooks 6 provided at the top of the collision mat to engage the staples. The hooks are preferably arranged to lie in the plane of the rubber sheet for the purpose 10 of bringing the latter as closely as possible against the hull of the vessel and may be conveniently secured to the springs 2.

The wooden planks permit screws to be inserted in them from the interior of the 15 vessel for the purpose of securing the mat to interior plates.

When required for use with holes of greater horizontal length than the width of the mat, the mat may be attached to vertical girders 20 as 8 which are used to bridge the hole. As shown in Figs. 5 and 6 one or more, say two, girders 8 of channel section are secured to the mat by bolts as 9, and the girders provided with ropes 10 whereby the mats may 25 be suspended over the side of the vessel.

In a modified construction of mat the springs are omitted and the mat provided with projections or spigots at one vertical edge and with tubular sockets at the other 30 edge, or other equivalent means, whereby two or more mats may be connected together so as to function as one large mat.

It will be understood that I do not desire myself to be limited to any particular type 35 of means for securing the mat to the hull, but that I may employ any convenient construction for accomplishing this result.

What I claim then is:—

1. In a collision mat for use on ships the 40 combination of a sheet of resilient material; a plurality of flat springs secured thereto tending to keep the mat flat but permitting it to be rolled up; and a plurality of rigid members secured transversely to said 45 springs; substantially as set forth.

2. In a collision mat for use on ships the combination of a sheet of resilient material; a plurality of flat springs secured thereto tending to keep the mat flat but permitting 50 it to be rolled up; a plurality of rigid members secured transversely to said springs; and a reinforcing tube along each of said rigid members, each tube having a projection at its one end adapted to engage with 55 a socket end of another tube to enable a plurality of mats to be united together.

3. In a collision mat for use on ships the combination of a sheet of resilient material; a plurality of flat springs secured thereto 60 tending to keep the mat flat but permitting it to be rolled up; a plurality of rigid members secured transversely to said springs;

and vertically disposed girder members secured to said rigid members.

4. In a collision mat for use on ships the 65 combination of a sheet of resilient material; a plurality of flat springs secured thereto tending to keep the mat flat but permitting it to be rolled up; a plurality of rigid members secured transversely to said springs; a 70 reinforcing tube along each of said rigid members, each tube having a projection at its one end adapted to engage with a socket end of another tube to enable a plurality of mats to be united together; and vertically 75 disposed girder members secured to said rigid members.

5. In a collision mat for use on ships the combination of a sheet of resilient material; a plurality of flat springs secured thereto 80 tending to keep the mat flat but permitting it to be rolled up; a plurality of rigid members secured transversely to said springs; and means for suspending it over the side of a ship.

6. In a collision mat for use on ships the combination of a sheet of resilient material; a plurality of flat springs secured thereto tending to keep the mat flat but permitting 90 it to be rolled up; a plurality of rigid members secured transversely to said springs; a reinforcing tube along each of said rigid members, each tube having a projection at its one end adapted to engage with a socket end of another tube to enable a 95 plurality of mats to be united together; vertically disposed girder members secured to said rigid members; and means for suspending it over the side of a ship.

7. In a collision mat for use on ships the 100 combination of a sheet of resilient material; a plurality of parallel and rigid members secured to said resilient material whereby the mat has flexibility in the one direction and rigidity in a direction at right angles 105 thereto; and a reinforcing tube along each of said rigid members, each tube having a projection at its one end adapted to engage with a socket end of another tube to enable a plurality of mats to be united together. 110

8. In a collision mat for use on ships, the combination of a sheet of resilient material; a plurality of parallel and rigid members secured to said resilient material whereby the mat has flexibility in the vertical direction and rigidity in the horizontal direction; and means on said mat whereby a plurality of similar mats may be united 115 together so as to function as one large mat having the character of a single mat and increased in length in the direction of its rigidity.

In testimony whereof I affix my signature.

CHARLES V. A. ELEY.
